CLAIM

The ornamental design for a bowl with a utensil retention feature, as shown and described.

DESCRIPTION

This Design Application is also related to co-pending U.S. Design patent application Ser. No. 29/428,185, filed on Jul. 27, 2012, entitled Bowl With Utensil Retention Feature; U.S. Design patent application Ser. No. 29/428,187, filed on Jul. 27, 2012, entitled Bowl With Utensil Retention Feature; U.S. Design patent application Ser. No. 29/428,188, filed on Jul. 27, 2012, entitled Bowl With Utensil Retention Feature; U.S. Design patent application Ser. No. 29/428,189, filed on Jul. 27, 2012, entitled Bowl With Utensil Retention Feature; U.S. Design patent application Ser. No. 29/428,215, filed on Jul. 27, 2012, entitled Bowl With Utensil Retention Feature; U.S. Design patent application Ser. No. 29/428,221, filed on Jul. 27, 2012, entitled Bowl With Utensil Retention Feature; U.S. Design patent application Ser. No. 29/428,222, filed on Jul. 27, 2012, entitled Bowl With Utensil Retention Feature; U.S. Design patent application Ser. No. 29/428,225, filed on Jul. 27, 2012, entitled Bowl With Utensil Retention Feature; U.S. Design patent application Ser. No. 29/428,227, filed on Jul. 27, 2012, entitled Bowl With Utensil Retention Feature; U.S. Design patent application Ser. No. 29/428,232, filed on Jul. 27, 2012, entitled Bowl With Utensil Retention Feature; U.S. Design patent application Ser. No. 29/428,240, filed on Jul. 27, 2012, entitled Bowl With Utensil Retention Feature; U.S. Design patent application Ser. No. 29/428,244, filed on Jul. 27, 2012, entitled Bowl With Utensil Retention Feature; U.S. Design patent application Ser. No. 29/428,248, filed on Jul. 27, 2012, entitled Bowl With Utensil Retention Feature; U.S. Design patent application Ser. No. 29/428,253, filed on Jul. 27, 2012, entitled Bowl With Utensil Retention Feature; U.S. Design patent application Ser. No. 29/428,256, filed on Jul. 27, 2012, entitled Bowl With Utensil Retention Feature; U.S. Design patent application Ser. No. 29/428,261, filed on Jul. 27, 2012, entitled Bowl With Utensil Retention Feature; U.S. Design patent application Ser. No. 29/428,270, filed on Jul. 27, 2012, entitled Bowl With Utensil Retention Feature; and U.S. Design patent application Ser. No. 29/428,279, filed on Jul. 27, 2012, entitled Bowl With Utensil Retention Feature. The disclosure of these Design Applications is considered part of and is incorporated by reference in the disclosure of this design application.

FIG. 1 is a top perspective view showing an embodiment of a bowl with a utensil retention feature;

FIG. 2 is a front view of FIG. 1;

FIG. 3 is a back view of FIG. 1;

FIG. 4 is a side view of FIG. 1;

FIG. 5 is another side view of FIG. 1;

FIG. 6 is a top view of FIG. 1;

FIG. 7 is a bottom view of FIG. 1;

FIG. 8 is a top perspective view showing a second embodiment of a bowl with a utensil retention feature;

FIG. 9 is a front view of FIG. 8;

FIG. 10 is a back view of FIG. 8;

FIG. 11 is a side view of FIG. 8;

FIG. 12 is another side view of FIG. 8;

FIG. 13 is a top view of FIG. 8;

FIG. 14 is a bottom view of FIG. 8;
FIG. 15 is a top perspective view showing a third embodiment
of a bowl with a utensil retention feature;
FIG. 16 is a front view of FIG. 15;
FIG. 17 is a back view of FIG. 15;
FIG. 18 is a side view of FIG. 15;
FIG. 19 is another side view of FIG. 15;

FIG. 20 is a top view of FIG. 15; and,
FIG. 21 is a bottom view of FIG. 15.
The broken lines of the preceding Figures are included for the
purpose of illustrating environment and form no part of the
claimed design.
